Application August 2, 1945, Serial No. 608,575

3 Claims. (Cl. 179—171.5)

1

The present application relates to apparatus for generating oscillatory energy and modulating the phase or frequency of the generated energy in accordance with signals. In the description reference will be made mainly to telegraphy and like signals but it will be understood that signals of other types such as voice or music may be used.

The object of my invention is improved generation and improved frequency modulation of oscillatory energy.

Means for generating oscillatory energy and modulating the frequency of the same are known in the prior art but as known are often complicated in nature and not too satisfactory in operation. A more detailed object of my invention is to provide a simple oscillation generator and frequency modulator. This is accomplished by making use of a pair of tubes in an improved oscillation generating circuit which circuit is so arranged that the frequency of the generated oscillations may be varied by signals readily. The arrangement then may be said to be a combined modulator and oscillator.

In modulators of this type the frequency of the generated oscillations is swung in accordance with the signals and occupies a prescribed frequency spectrum in which it must be maintained. This requires that the mean frequency about which the oscillations are swung be stabilized. A further object of my invention is to provide a combined oscillator and frequency modulator including means whereby the mean frequency of operation is stabilized or fixed, and yet the arrangement is such that the frequency of the oscillations generated can be readily modulated in accordance with signals the required amount.

In many simplified modulation systems when the frequency or phase of the oscillatory energy is modulated undesired amplitude modulation in accordance with signals and power supply variations is encountered. An object of my invention is to so arrange or balance my simplified modulation circuits that the undesired amplitude modulation is bucked out or substantially eliminated so that the amount of limiting needed in the modulator output is lessened. This is accomplished in accordance with my invention by using a pair of tubes in an oscillation generating circuit and by modulating the tubes differentially so that in so far as the modulation potentials and power supply voltages are concerned the system is balanced.

In my system a pair of electron discharge

2

devices have their anodes associated with a tank circuit and have regeneratively coupled control grids, and also have other grids coupled by a phase shifting network to the tank circuit so that a phase quadrature relation is established between the radio frequency potential on the control grid and the other grid of each tube, the phase quadrature being advanced in one tube and being retarded, that is, in reverse direction in the other tube so that the output of each tube is of different phase. One tube has its phase ahead of the carrier and the other tube has its phase behind the carrier wave. When the tubes are excited symmetrically to have equal gains, they operate at a fixed frequency which may be stabilized by a tuned circuit. Differential modulation of the tubes changes the gain of the tubes and permits the frequency of operation thereof to swing towards the frequency at which the tube having the highest gain would normally operate. A feature of my invention is the use of the network as described below supplying the quadrature excitation voltages to one set of grids in the two tubes in addition to the regenerative feedback supplying voltages to another set of grids in regenerative sense.

Phase shifters are used to supply the phase quadrature voltages to the screen grids and in my system phase shifters composed entirely of resistances and condensers which may be considered aperiodic since they are not tuned to the operating frequency are used, so that the only tuned circuit is the tank circuit from which the voltages applied by the phase shifters to the grids is derived. Phase shifters of this type are not affected by stray fields and as a consequence are more reliable in operation. The phase shift produced is substantially constant during operation when the capacitors and resistors have low temperature coefficients. The amount of phase shift produced is easily calculated and adjusted as desired.

The manner in which the above objects and others are attained will be described in detail hereinafter. In this description reference will be made to the drawings wherein Figs. 1 and 2 each illustrate a different embodiment of my improved apparatus for generating oscillatory energy and modulating the phase or frequency of the same in accordance with signals.

In Figs. 1 and 2 the pair of electron discharge devices have their anodes coupled in push-pull relation to the tank circuit and their screen grids coupled to the tank circuit by a phase shifting network.

In both embodiments a point intermediate the ends of the tank circuit is coupled to the cathodes of the tubes and the control grids of the respective tubes are cross coupled to the tank circuit to operate in the oscillation generating circuits approximately 180° out of phase with respect to each other and to the radio frequency voltage on the anodes of the said respective tubes.

In the embodiment illustrated in Fig. 1 a keyed tripping circuit and additional modulating circuits are arranged to be coupled to the tube electrodes differentially for modulation purposes. This modulating circuit may be used in like manner in the system of Fig. 2.

In Fig. 1 a pair of electron discharge tubes V_1 and V_2 have their anodes 2 and 4 coupled to opposite ends of a tuned tank circuit comprising capacitor C_1 and inductor L_1 . An output circuit in the form of an inductance L_2 may be coupled to L_1 although other coupling means may be used if desired. A point centrally located between the ends of inductance L_1 is connected to the positive terminal of a source of direct current potential and to ground and the cathodes of tubes V_1 and V_2 by a capacitor C_{10} which bypasses voltages of the generated frequency. This point is also connected to a point intermediate the sections of capacitor C_1 by a resistance R that uncouples the capacitive and inductive branches of the tank circuit so that split tuning will not take place. In other words, resistor R prevents the upper and lower halves of the tank circuit from being resonant at different frequencies in case their constants are not similar. The use of R is desirable in order that all parts of the tuning condenser be kept at the same direct current potential and thereby prevents arcing or condenser breakdown. It also increases the rating of the condenser since it has only to be insulated for the A. C. voltage on it.

A phase shifting network comprising series capacitors C_2 and C_3 and shunting resistances R_3 and R_4 with R_5 connect a point on the inductance L_1 to the screen grid 8 of tube V_1 and the screen grid 10 of tube V_2 . These connections include radio frequency bypassing and coupling and direct current and audio frequency blocking condensers C_4 and C_5 . As illustrated the tap on L_1 and the lead to anode 2 are on the same side of the grounded point on L_1 . The tap may be moved to the other side of the grounded point without altering the principle of operation. Radio frequency bypass condensers C_6 and C_7 couple the low radio frequency voltage ends of resistances R_4 and R_5 to the cathodes of the tubes. Capacitors C_6 and C_7 are large and are used to complete the radio frequency circuits of the phase shifting networks but are small enough to block currents of the frequency of the modulating potentials applied from any desired means, such as a tripping circuit or transformer, to leads 1 and 3, and thence differentially to the screen grids 8 and 10 through resistors R_4 and R_5 . The control grids 14 and 16 are cross-coupled by coupling condensers 11 and 13, to points on L_1 at opposite sides of the point thereon put at radio frequency ground potential by condenser C_{10} . A common cathode biasing resistance R_1 is shunted by a radio frequency bypassing capacitor C_9 . Biasing resistances R_8 and R_9 are connected between the control grids 14 and 16 of the tubes and ground. When the electrodes 8 and 10 are screening electrodes the modulating potentials applied to the leads 1 and 3 may be superimposed on direct current positive potentials of the desired

value. A modulation source A for telephone may be coupled to a transformer T_1 primary winding. The secondary winding of this transformer is coupled to points on the resistances R_8 and R_9 . A switch S may be included in this coupling. The resistors R_8 and R_9 are grid leak resistances. The secondary winding of transformer T_1 is tapped up on these resistors to points at which the resistance matches the impedance of the transformer secondary winding.

The common cathode resistance R_1 maintains substantially constant bias on the control grids 14 and 16 of tubes V_1 and V_2 since the sum of the currents through both tubes is substantially constant if the modulating potentials are properly balanced. In my system they are balanced by proper selection of resistances R_4 and R_5 and condensers C_8 and C_9 and application of proper modulating potentials to leads 1 and 3.

Consider the system as described as an oscillation generator and assume the electrodes are energized and tank circuit C_1L_1 tuned to the desired operating frequency. Oscillations are generated due to regenerative feedback between the anode and control grid in each tube. Note the R. F. voltages are opposed on the anodes—reversed and opposed on the control grids so that the set up is right for regenerative operation. Each tube as connected is a regenerative generator. The two tubes are entrained by the tank circuit L_1C_1 to operate as a single generator operating at a common frequency.

The screen grids 8 and 10 of tubes V_1 and V_2 are coupled by phase shifting networks C_2C_3 , R_3R_4 with R_5 , to a voltage point on L_1 , whereas the radio frequency voltage phase is the same as the phase of the voltage on the anode 2. The phase of this voltage as applied to the grid 8, however, is relatively advanced about 90° by the phase shifting network. The potential on the control grid 14 however is 180° out of phase with respect to the potential on the anode 2. As a consequence the screen grid 8 and control grid 14 are excited substantially in phase quadrature relation. The sum or resultant of the excitation on the control grid 14 and the screen grid 8 of the tube V_1 is lagging something less than 90°, say 45° displaced relative to the voltage in the circuit C_1L_1 , so that the phase of the anode current output of tube V_1 is lagging the phase of the oscillating current in tank circuit C_1L_1 by about 45°.

The phase shifting network C_2 , C_3 , R_3 , and R_4 with R_5 also supplies a voltage to the screen grid 10 of tube V_2 which is advanced about 90° ahead of the phase of the voltage of the anode 2 of tube V_1 but which is retarded about 90° behind the phase of the voltage of the anode 4 of tube V_2 since the anode voltage of tube V_2 is 180° out of phase with respect to the anode voltage of tube V_1 . The phase of the voltage on control grid 16 of tube V_2 is the same as that on the screen grid 10 of tube V_2 except for the 90° phase advance due to the phase shifting network. The sum of the resultant A. C. voltage on the control grid 16 and the screen grid 10 is leading, this time something less than 90°, say 45°, relative to the phase of the current in the tank circuit C_1L_1 so that the anode current output of tube V_2 is say 45° leading this time the phase of the oscillations in the tank circuit C_1L_1 .

The frequency of operation of the individual tubes and of the tubes as entrained by the circuits depends on the phase relation of the radio frequency voltages on the tube electrodes and on the state of conductivity of the respective tubes.

If like direct current potentials are applied to the screen grids and the phase of the electrode voltages are as described above the system will oscillate at a frequency depending primarily upon the tuning of circuit C1L1.

The excitation energy from the anode 2 end of the tuned circuit to the screen grid 18 is relatively advanced 90° by the phase shifting network. The excitation energy to the screen grid 10 of V2 is also relatively advanced by its phase shifting network but is initially 180° out of phase with respect to the anode 4 voltage so that the excitation on the screen grid 10 is lagging the anode 4 voltage by about 90°.

The phase of the oscillations generated in the tank circuit C1L1 is the resultant of the anode power delivered to it from the tubes V1 and V2. Similarly the phase of the power delivered by the tubes V1 and V2 is the resultant of the phase of the control grid excitation voltages by way of condensers 11 and 13, and the excitation voltages on the screen grids 8 and 10. Since the resultant grid excitation in tube V1 is lagging it delivers power of lagging phase angle to the tank circuit C1L1. In contrast since the resultant grid excitation in tube V2 is leading it delivers power of leading phase angle to the tank circuit C1L1. As long as the tubes V1/V2 deliver equal power as is the case when no modulation is present, then the oscillator operates at the normal frequency to which C1L1 are tuned. However, if one tube delivers more power than the other the oscillator frequency will change by "pulling" the frequency one way or the other. For example, if during the modulation cycle the screen grid of tube V1 is biased more positive and the screen grid of tube V2 is less positive then since V1 delivers phase retarded power and more power than tube V2 the frequency of the oscillator will be decreased. On the other hand, if the power output of the tube V2 is increased by making its screen grid 10 more positive and the potential of screen grid 8 of tube V1 is made less positive, since the phase of the power from tube V2 is leading the frequency of the oscillator will be increased. Modulation potential applied differentially to the screen grid electrodes by leads 1 and 3 results in frequency modulation of the oscillations generated in accordance with the modulation potentials. Amplitude variation of the modulated radio frequency by the signals or by power supply variations are corrected due to the differential action. The modulation potentials may represent telegraphy code or similar signals or music or voice. The latter may be applied by a transformer secondary winding tapped to supply the direct current potentials for the screen grids or telegraph signals may be applied by control circuits as disclosed in my U. S. Patent #2,326,314. Modulation may also or alternatively be applied from source A differentially to the control grids 14 and 16, when switch S is closed.

In Fig. 1 I have shown somewhat completely modulating and keying means which may be used with the oscillation generators of Figs. 1 and 2. Switches S1 and S2 are used to switch the modulator to the "phone" source, contacts a, through transformer T2 or to the tripping circuit tubes V3 and V4 contacts b. A double pole triple throw switch may be used for this purpose. The leads 1 and 3 may be connected to the movable members of the triple throw, double pole switch S1, S2. A pair of the contacts a of this switch may be connected by a transformer T2 to a source B

of modulating potentials such as those representing voice signals and the like. When the switch is on contacts b the leads 1 and 3 may be connected to the resistors 45 and 46 of a tripping keying circuit such as disclosed more in detail in my U. S. application Serial #521,907, filed February 11, 1944. This keyed tripping or switching circuit including tubes V3 and V4 supplies at the leads 30 and 32 direct current potentials which are applied by way of leads 1 and 3 to the screening electrodes 8 and 10. The direct current potentials are made of a value such as to alternately key the tubes V1 and V2 from a more conductive condition to a less conductive or a non-conductive condition. Preferably the potentials swing from a positive value at which the tubes are conductive to a negative value at which they are cut off.

The tripping and keying circuit comprises tubes V3 and V4 with their anodes and control grids cross-coupled by resistances 41 and 42 in such a way that the potential drops in the anode resistors 43 and 44 connected between the anodes are applied respectively to the grids of the tubes V4 and V3. When one of these tubes draws current the grid of the other thereof is made more negative by applying the potential drop at the anode of the said one tube to the grid of the other tube. In this manner current is caused to flow through tube V3 while tube V4 is cut off or vice versa.

A point intermediate the resistances 43 and 44 is connected to the positive terminal of a source of direct current potential. A point intermediate the terminals of resistances 45 and 46 is connected to a point on a potentiometer resistance 49 shunting a source of potential B2 the positive terminal of which is grounded. This source of potential is shunted by a condenser C12 of a size sufficient to bypass the source B2 for potentials of the keying frequency. The resistances 45 and 46 which are potentiometers have points thereon connected to the leads 30 and 32 and thence by leads 1 and 3 to the screening electrodes of tubes V1 and V2 for modulation purposes. The outer ends of the resistances 45 and 46 are connected to an alternating varying positive voltage source, i. e., to the anodes of tubes V3 and V4 which, as described hereinafter, swing alternately positive and less positive as the control grids of the tubes or one thereof is controlled by signal potentials. The potential on the leads 30 and 32 therefore is a resultant of the potentials on the anodes of tubes V3 and V4 and of the potential from the main direct current source DC and the potential derived from source B2 by way of the potentiometer 49 and also of the conductivity of the tubes V3 and V4.

The tripping tubes V3 and V4 have their control grids coupled respectively by resistances 53 and 61, and 59 and 63, to ground, and by resistance 65 shunted by a bypass condenser 67 of low impedance to potentials of the keying frequency to the cathodes of tubes V3 and V4. 61 and 63 are potentiometer resistances with a point on resistance 61 connected by switch S3 either to the positive terminal of a source B3 or to ground. A point on potentiometer resistance 63 is connected to a source of signals, for example, keyed pulse energy, or keyed direct current or keyed alternating current energy. The other terminal of the resistance 63 is connected to ground so that the signals are applied to the control grid of tube V4 with respect to its cathode.

The source B3 is sometimes necessary to apply a fixed negative bias to the grid of tube V3 in order to get positive tripping action. The arrangement is such that the tube V3 is biased to cutoff in the absence of marking and spacing signals either by the drop in potential in resistances 58 and 61 or if necessary by negative potential from the source B3 with switch S3 on contact K1 instead of on K2. The current then is switched through tube V4 and the resistances 43, 44, 45 10 and 46, the direct current source and the tap on potentiometer 49, etc., are such that the potential at the anode of V4 drops the required amount. This falling potential is fed to the screen grid 10 by leads 32 and 3 and is sufficient to swing the screen grid 10 negative or less positive enough to block or bias tube V2 and cut off or reduce current therethrough. At the same time the anode of tube V3 swings more positive because current through tube V3 is cut off or reduced, and its anode is at or near the direct current source potential. The elements are dimensioned and adjusted to values such that the screen grid for tube V1 is made positive by this positive potential supplied by leads 30 and 1, and tube V1 draws current so that oscillations of a lagging phase are supplied by tube V1 to the tank circuit and the frequency of operation of the system goes down and oscillations of one frequency are transmitted. They might well represent "no signal" or "space" signal.

Now when keying signals are applied an alternating current or direct current potential fed at the input and applied to the grid of tube V4 switches the current through tube V3 by blocking or biasing tube V4 and by virtue of the cross-couplings 42 and 41. With the current switched through tube V3 and cut off in tube V4 a more negative potential is fed by leads 30 and 1 to the screen grid 8 of tube V1 and a more positive potential is applied from the anode of tube V4 by leads 32 and 3 to the screen grid 10 of tube V2 and this tube V2 becomes conductive to supply oscillations in the tank circuit L1C1 of leading phase so that the frequency of the oscillations becomes higher and oscillations of this frequency may represent the marking condition.

Alternating current or direct current may be used for keying purposes. If alternating current pulses are applied to the control grid of tube V4, through which the current is switched in the absence of signals, the positive excursions of the alternating current have no effect because the tube V4 is already drawing maximum current. The negative cycles of the keyed alternating current however, make the grid of tube V4 negative to cut off current therein and switch the same through tube V3 as described hereinbefore. Adjustment of the point on potentiometer 61 permits operation such that the positive bias on the tube V4 is overcome by the applied signals to insure the current switching action. If necessary more negative potential may be applied to the grid of V3 from the source B3 by putting the switch S3 on contact K1.

I have found that when telephony signals or tone modulation is applied to the screen grids of a modulator, distortion in the modulated output may result. In Fig. 1 I show a circuit arrangement by which the signal modulation may be applied to the control grids of the modulator tubes as well as to the screen grids. In this embodiment phone signals or tone signals may be applied to the control grids and telephony or phone or tone signals may be applied to the

screen grids as in the prior embodiment. Application of the telephony or tone modulation to the control grids produces substantially undistorted voice or sine wave modulation of the output in accordance with the signals.

The potentiometer resistance 71 supplies the desired direct current biasing potential by way of the secondary winding of transformer T2 to the screening electrodes when the switches S1 and S2 are on the *a* contacts. The modulating potentials are then superposed on the positive bias and applied from source B differentially by way of leads 1 and 3 to the screening electrodes 8 and 10. The modulating potentials may represent tone or phone signals. During this operation and when the switches S1 and S2 are on the *b* contacts the switch S is open to disconnect the source A from the control grids of the tubes V1 and V2.

When telephony signals or tone modulation is applied to the screen grids 8 and 10 of my system some distortion in the modulated output may result.

In Fig. 1 I show a circuit arrangement by which the signal modulation may be applied to the control grids of the modulator tubes instead of to the screen grids. In this embodiment phone signals or tone signals may be applied to the control grids from source A by way of transformer T1 and resistances R8 and R9 when the switch S is closed. Application of the telephony or tone modulation to the control grids produces substantially undistorted voice or sine wave modulation of the frequency of the output in accordance with the signals. Then the switches S1 and S2 may be placed on the *c* contacts to supply an adjustable D. C. potential to the screen grids 8 and 10.

If desired tone or phone modulation from source A may take place simultaneously with telegraphy modulation by signals applied to the leads 49 and 51. To do this the switch S is closed as stated above and the switches S1 and S2 are moved to the *b* contacts so that the output of the tone keyer is applied to the screen grids while the output of the phone or signal source A is applied to the control grids.

I have shown an improved signalling system of this type in Fig. 2. In Fig. 2 I have used reference numerals corresponding to those used in Fig. 1. The arrangement in general is as shown in Fig. 1. The tripping circuit is shown by a rectangle but the details there may be substantially as in Fig. 1.

The source B2 is omitted in the practical arrangement illustrated in Fig. 2 and the potentiometer resistance 49' shunted by condenser C10 now also is in shunt to the main direct current source.

The radio frequency circuits are substantially similar to those in Fig. 1. However, in the arrangement of Fig. 2 I have made the oscillation generator more stable so that its average or mean frequency is more constant in spite of voltage changes and ambient temperature changes. To do this I include resistors R13 and R14 in the anode leads to the tank circuit. Moreover, to further enhance stability the oscillator tank circuit C1'L1 is built with a relatively large capacitive reactance C1 and low inductive reactance L1. The condenser C1 and the coil L1 are both constructed of materials and methods resulting in low coefficients of expansion. Moreover, the tank circuit L1C1 is enclosed in a temperature control box TCB, the interior of which

is held at a substantially constant temperature by means known in the art but not shown here. The ends of the tank circuit are as stated connected to the anodes 2 and 4 by the damping resistors R13 and R14. To further improve the operating characteristics, the tank circuit L1 is coupled to the control grid 15 of an electron discharge device V5 through resistor 76 and coupling condenser 72. 82 is the grid leak resistance and 84 is the cathode return resistance shunted by condenser 85. Anode potential is supplied from the main source through resistance 87. The output of the system is then taken from the anode and cathode of the stage V5 by way of ground and condenser 89.

The constant temperature at which the tank circuit C1L1 is held holds the capacity inductance thereof substantially constant. The resistances R13 and R14 and 76 act to minimize any effect of the tubes V1, V2 and V5 on the average frequency of the oscillations generated in the tank circuit due to temperature changes in the tubes and to changes in tube characteristics when tubes are changed. It has been found that connecting a resistance across a parallel tuned circuit does not change its frequency response. However, if a reactance, inductive or capacitive, is connected across a parallel tuned circuit then its frequency response is changed. The anodes of tubes V1 and V2 present a considerable amount of capacitive reactance when connected across the tank circuit as shown in Fig. 1. In this case a change of tubes or a change of tube temperature will change the anode to suppressor grid capacity and consequently it will change the oscillator tank circuit tuning. This, of course, changes the oscillator frequency. When resistors R13 and R14 are connected between the tank circuit and the anodes of V1 and V2 as shown in Fig. 2, a variation of tube anode capacity will not change the tank circuit tuning and the oscillator frequency to such an extent. The larger resistors R13 and R14 are made the less the tube capacity will affect the oscillator frequency. It would be advisable to make R13 and R14 as large as possible and still maintain oscillations in the oscillator tank circuit. The tube grid connections are usually made quite far down on the coil toward the center point and therefore do not materially affect the oscillator frequency. The anodes are usually connected to the ends or near the ends of the tank circuit and consequently they have a much greater effect on the oscillator frequency. Also, the capacities of the grids are usually much less than that of the anodes. It can also be said that the greater the impedance (resistance and reactance) that is connected across a parallel tuned circuit the less effect it will have on the tuning of the tank circuit.

The resistances R13 and R14 also will cut down the amount of frequency deviation possible. However, this deviation is considered ample anyway so that it is desirable to sacrifice some of it in the interest of an average constant frequency. It may also be noted that the resistor 76 is tapped on inductance L1 at a point equally opposite the tapping point of condenser C2 (in the phase shift network) so that the two approximately balance their effect on L1. The output tube V5 has been added to lighten the load on the tank circuit C1L1 to thereby aid in holding a more constant average frequency. The load is lightened because the excitation energy required by tube V5 is quite small and any small variation in it is smoothed out by resistor 76. The series resistances R13

and R14 should be made as large as practical and still have satisfactory operation of the frequency modulator circuit during modulation.

The source A and the tripping circuit are connected and operate substantially as described above. The modulation source B however is omitted. With the switches S1 and S2 in the position shown, i. e., on contacts c direct current biasing and operating potentials only are applied to the screening electrodes. The switch S may then be closed and differential modulation of the control grid potentials takes place to modulate the frequency of the oscillations generated as described above by making the tube V1 say with the phase lagging excitation on the control grid and screen grid predominate when the modulation swings in one direction, and to make the other tube V2 with the sum of the voltage on the screen grid and control grid of leading phase predominate when the modulation swings in the other direction.

With switches S1 and S2 moved on the b contacts the tripping circuit is connected to the leads 3 and 1 and thence to screen grids 10 and 8 to modulate the generated oscillations in accordance with telegraphy signals as described hereinbefore. Then the output comprises telegraphy modulated oscillations which may also be modulated by tone signals from source A. With the switches S open telegraphy signals only are developed by the keying and tripping circuit.

What I claim is:

1. In apparatus for generating and modulating oscillatory energy, two electron tubes each having an anode, a cathode, a control grid and an auxiliary grid, a tank circuit parallel tuned substantially to the desired operating frequency, means coupling each of said tubes and tank circuit in a regenerative oscillation generator including said tank circuit coupling the anodes and cathodes of said tubes in pushpull relation and coupling the control grids and cathodes of said tubes in pushpull relation, the arrangement being such that the phases of the voltages of the regenerated frequency on the anode of each tube are displaced in phase about 180 degrees with respect to the phase of the generated voltages on the grid of the same tube, additional couplings between said tank circuit and said auxiliary electrodes such that when oscillatory energy of the desired operating frequency is developed in said tubes and tank circuit the phases of the voltages of the generated frequency on the control grid and auxiliary grid of each tube are displaced by substantially 90°, and means for differentially modulating the gains of said tubes in accordance with signals.

2. Apparatus as recited in claim 1 wherein impedances are interposed in the coupling between the tank circuit and the anode of each tube.

3. In apparatus for generating and frequency modulating oscillatory energy, two electron tubes each having an anode, a cathode, a control grid and an auxiliary grid, a tank circuit parallel tuned substantially to the desired operating frequency, means including said tank circuit coupling the anodes, cathodes and control grids in push pull relation, said push pull couplings to the control grids being crossed relative to said push pull couplings to said anodes so that when oscillatory energy of the desired operating frequency is developed in said tubes and tank circuit the phase of the voltages of the generated frequency on the anode of each tube is substantially 180° out of phase relative to the phase of

the voltage on the grid of each tube to provide regeneration, a phase shifting network coupling said tank circuit to said auxiliary electrodes so that when oscillatory energy of the desired operating frequency is developed in said tubes and tank circuit the phases of the voltages of the generated frequency on the control grid and aux-

iliary grid of each tube are displaced by substantially 90°, an output circuit coupled to said tank circuit, two sources of modulating potentials, and means for coupling one of said sources differentially to the control grids and the other of said sources differentially to said auxiliary grids.

GEORGE L. USSELMAN.
